UNITED STATES PATENT OFFICE.

JOSEPH C. COULOMBE, OF DRACUT, MASSACHUSETTS.

LIQUID-FEEDING DEVICE.

Application filed December 15, 1919. Serial No. 345,025.

To all whom it may concern:

Be it known that I, JOSEPH C. COULOMBE, citizen of the United States of America, and resident of Dracut, in the county of 5 Middlesex and State of Massachusetts, have invented new and useful Improvements in Liquid-Feeding Devices, of which the following is a specification.

This invention relates to liquid fuel feeding devices, generally known as "vacuum feeds," of the kind commonly used in automobiles for raising gasoline or other liquid fuel from a supply tank at a low level to a level above the carburetor of the engine, 10 to which carburetor the fuel is delivered from the feeding device by gravity. The "vacuum" or suction for operating such devices is usually developed in the intake manifold of the engine, although the sub- 15 atmospheric pressure may be obtained by other means.

The invention consists in certain modifications of and improvements upon vacuum operated liquid feeding devices of the type 20 shown in my applications for Letters Patent of the United States, Ser. No. 229,538, filed April 19, 1918, and Serial No. 72,193, filed January 15, 1916, and its object is to simplify and improve the construction and 25 operation of such devices in the manner hereinafter more fully described and particularly pointed out in the claims.

In the accompanying drawings which illustrate certain embodiments of my invention,

Figure 1 is a vertical section of the liquid feeding device;

Figure 2 is a top plan view of the same;

Figure 3 is an enlarged detail view of the 40 main valve, partly in side elevation and partly in section; and

Figure 4 is a detail, partly in side elevation and partly in section, showing a modification.

5 Figure 1 represents the side walls of the outer casing, or tank, preferably cylindrically formed of sheet metal. The bottom 6 of the tank is formed of pressed sheet metal slightly concaved and tightly fitted to the sidewalls 5. The top 7 of the tank is also made of pressed sheet metal fitted to walls 5 by a close, but not a gas tight joint, and formed with an integral dome-like protuberance 8, the sides of which are flat as shown 55 at 9 and 10 to receive the pipe fittings or

nipples to which the suction pipe and the liquid supply pipe are connected.

The joint between the flange 7^a of the top and the upper edge of the tank walls 5 is sufficiently loose to admit air, but closes the 60 tank against dust and dirt.

The pipe fitting 11, to which is connected the suction pipe or vacuum pipe leading to the intake manifold of the engine or other suction producing means (not shown), is 65 tightly connected to the flat wall 9 by a head 12 on the inside of the wall and a nut 13 on the outside of the wall. The pipe fitting 14, which is connected to the liquid fuel supply (not shown) is tightly fitted to the flat wall 10 by a head 15 on the inside of the wall and a nut 16 on the outside of the wall. The passage 17 through fitting 14 connects with the passage through fitting 18 which is screwed 70 into the side of the head 15.

75 At the bottom of the tank the final outlet port is through pipe fitting 19 set into an aperture in the bottom 6 and connected to the pipe (not shown) leading to the carburetor. 20 is a strainer mounted on the head 80 of fitting 19.

The inner casing 21 constitutes a vacuum or suction chamber. Its top is tightly fitted into a shoulder 22 of the tank top 7, and its bottom is closed by a plate 23 screwed to a 85 ring 24 with a gas tight gasket or packing 25 between them. The ring 24 is formed with a flange tightly fitting the cylindrical walls of casing 21.

26 is a liquid seal chamber or float control chamber, and consists of an inverted cup-like casing supported on a post 27 which is fixedly mounted on plate 23. A float 28, which is preferably of cork, is arranged in the float control chamber 26 to slide freely 95 on post 27 as a guide. The float controls a valve 29 between the suction chamber 21 and the distributing chamber 30 in the lower part of tank 5. The valve 29 cooperates with an inclined valve seat or collar 31 100 secured to the bottom plate 23 of the suction chamber; and an air tube 32 rises from the highest part of the inclined valve seat to a point above the normal level of the liquid in the suction chamber for a purpose herein- 105 after explained.

110 As the upper edge of tank 5 is not sealed to the top 7 but fits loosely the distributing chamber 30 is always at substantially atmos- pheric pressure.

Centrally arranged in the valve 29 is a relief valve 33 mounted on a screw threaded stem 34 which extends through the relief valve seat in the valve 29 and is screwed into the end of the main valve stem 35. The end of stem 35 is countersunk and provided with relief ports 36' to permit the escape of air through the relief valve when the end of stem 35 is forced down against the main valve 29. The valve 29 is loose on stem 34 and is therefore free to accommodate itself to its seat. The main valve stem 35 is connected to one end of a lever 36 pivoted on a bracket 37, as at 38, the other end 15 of the lever being connected by a slot and pin connection 39, 40, to the bottom of the float 28.

The inverted cup 26 of the liquid seal chamber or float control chamber has an annular cup or flange 41 extending around the outside and forming a trough or gutter; and within the wall of the inverted cup 26 is an upwardly extending flange or shell 42. Perforations 43 afford communication connecting the trough 41 with the space between the walls of cup 26 and the flange 42. The flange 42 extends nearly to the top of the float control chamber.

Below the gasoline or liquid fuel inlet passage 17 is a valve 44, mounted on a float 45, adapted to rise and cut off the supply in case through any mishance the liquid should rise in chamber 21 sufficiently above a predetermined high level to actuate float 45. The float 45 is supported in a housing 46 which has a slot 47 on the side toward the gutter 41, thereby deflecting the inflowing liquid into gutter 41.

Secured to the bottom of float 28 is a shallow baffle cup 48 which terminates below the lower edge of the inverted cup 26 when the float is in its lowermost position, and extends above and outside of the edge of cup 26 when the float is in its uppermost position. In the bottom of the baffle cup 48 is a hole through spout 49, which is made with a jagged or corrugated edge as shown.

To hold and guide the main valve 29 and relief valve 33 during their operation, a link 50 is provided, pivoted at one end to lugs 51 on the bottom of plate 23, and at the other end pivoted to the body of valve 33. The link 50 has a shoulder 52 which serves as a stop to engage the lower edge of valve 29 and prevent the lower edge of the valve from tipping farther away from its seat than the upper edge when the valve is opened, as it would tend to do under the influence of the flowing liquid. This insures a free passage for the flow of air through the air tube.

The operation of the device is as follows: With the parts in the position shown in Fig. 1, and the fitting 11 connected to the

intake manifold of the engine or other vacuum producing means, and the fitting 14 connected to the liquid fuel supply, liquid fuel will be drawn from the supply tank through passage 17 into the suction chamber 21. When the level of the liquid rises to the lower edge of the inverted cup 26 it will seal the cup and continue to rise in chamber 21, and also less rapidly in the liquid seal chamber 26, in which the air is now trapped as the holes 43 are sealed by the liquid in trough 41. There will therefore be a difference in level between the liquid in chamber 21 and in chamber 26, which difference in level is automatically controlled by the holes 43, which will allow air in chamber 26 to escape when it exceeds a predetermined pressure thus permitting the level of the liquid in chamber 26 gradually to rise.

As soon as the level of the liquid rises sufficiently to lift the float 28, the small relief valve 33 will be opened, admitting air from chamber 30 and reducing the vacuum (increasing the pressure) in suction chamber 21. The vacuum now being broken the float 28 is free to rise and easily forces the main valve 29 off from its seat, permitting the liquid in vacuum chamber 21 to flow by gravity into distributing chamber 30. The quick flow of the fluid through valve 29 is facilitated by the inclined valve 29 and the air tube 32 leading from the highest part of the valve opening, as the liquid seeks the lowest part and the air rising through the same valve opening is permitted to pass substantially unobstructed by flowing liquid, up through the air pipe 32 into chamber 21.

The float 28 will remain in its elevated position, being held by the conditions of relative pressure between chambers 21 and 26, until the level of the liquid in chamber 21 falls below the spout 49. Thereupon the liquid seal will be broken in cup 48 (the corrugated edge of spout 49 helping the better to break the seal), the relative pressures between chambers 21 and 26 will tend to equalize, the contents of the chamber 26 will be discharged and will flow by gravity through the valve 29, and the float will be released and will drop with a quick motion and close valve 29. The condition of partial vacuum will then be reestablished in suction chamber 21 and the cycle of operations repeated. It will be understood that the liquid fuel flows from distributing chamber 30 to the carburetor by gravity.

In case the level of the liquid in the suction chamber 21 should rise too high the valve 44 carried by float 45 will close and cut off the supply through inlet passage 17.

With the structure above described, the top 7 of the tank is made of a single piece of pressed sheet metal instead of requiring a

casting as in my said former application, and the pipe fittings are merely screw machine parts fastened to the top by nuts, thus simplifying and reducing the cost of manufacture. Similarly the bottom 6 is a single piece of pressed sheet metal, the outlet opening of which is shaped to hold the fitting 19.

The float 45 and valve 44 serve to cut off the liquid fuel supply and prevent the flooding of the device under unusual conditions such as the elevation of the supply tank above the vacuum feed device, when the automobile is on an incline, which might result in the flow of the liquid fuel into the device by gravity. The slot 47 in the side of the housing 46 insures the filling of the cup or trough 41 with the liquid.

Inasmuch as the inverted cup or liquid seal chamber 26 is supported on post 27, which is fixed to the bottom plate 23 of the suction chamber, the inverted cup, float, valve, valve-operating connections and all associated parts can be removed as a unit for repair or replacement by merely unscrewing and removing the detachable bottom plate 23 from suction tank 21. The post 27 also, being supported at the lower end instead of its top end, extends completely through the float and serves as a guide throughout the whole length of the float in all positions of the float.

The inclined valve 29 and valve seat 31, allow the suction tank to empty more quickly than a horizontal valve, because with a horizontal valve the air has to rise directly through the downwardly flowing liquid, whereas with a valve lower at one edge than at the other the liquid tends to flow to the lowest part of the valve opening while the air rises through the upper part, and instead of then bubbling up through the liquid in the suction chamber, is carried by the air tube 32 to a point above the level of the liquid. This function could be secured by arranging the valve at any angle to a horizontal plane, even a right angle, as well as at the angle of inclination illustrated in the drawings.

The strainer screen 20 at the final outlet is readily accessible and may be removed for cleaning or repair by merely taking out the suction tank from the outer tank 5.

In the modification shown in Fig. 4, the air tube 32^a instead of being fixed to the bottom plate 23 of the suction chamber is fixed to the valve stem 35. Its function and mode of operation in carrying off the rising air when the valve is opened, are substantially the same as in the form already described.

I claim:

1. A liquid feeding device comprising a distributing chamber, a suction chamber, a discharge passage connecting said chambers, an inclined valve seat for the discharge pas-

sage, a valve normally seated upon the inclined valve seat, said valve when seated being at an angle to a horizontal plane, a float member in the suction chamber and connections actuatable by said float member for controlling the opening and closing movements of said inclined valve. 70

2. A liquid feeding device comprising a distributing tank, a suction tank removably connected to the distributing tank and having a detachable bottom, a post fixed to the detachable bottom, a float guided by said post, and a valve actuated by the float, said post, float, valve and valve mechanism being carried by said detachable bottom and removable therewith. 75

3. A liquid feeding device comprising a distributing tank, a suction tank removably connected to the distributing tank and having a detachable bottom, a post fixed to the detachable bottom, a float guided by said post, a liquid seal chamber fixed to the upper end of the post having a closed top and open bottom encircling the float, and a valve actuated by the float, said post, liquid seal chamber, float, valve and valve mechanism being carried by said detachable bottom and removable therewith. 80

4. A liquid feeding device comprising a distributing chamber, a suction chamber, a discharge passage leading from the suction chamber to the distributing chamber, an inclined valve seat for said discharge passage, a main valve member normally seated upon the inclined valve seat, said valve when seated being at an angle to a horizontal plane, an auxiliary valve for closing and opening in said main valve, a float member in the suction chamber and connections actuatable by said float member for first opening said auxiliary valve and for thereafter opening said main valve. 95

5. A liquid feeding device comprising a distributing chamber, a suction chamber above the distributing chamber, a valve between said chambers, and a float in the suction chamber to actuate the valve, said valve and its seat being at an angle to a horizontal plane to facilitate the quick emptying of liquid from the suction chamber into the distributing chamber, and an air tube leading from the higher part of the valve opening to a point above the normal level of liquid in the suction chamber. 105

6. A liquid feeding device comprising a tank having a top made of a single piece of pressed sheet metal formed with a dome-like protuberance, said protuberance having an opening in its side wall, and a pipe fitting comprising an externally threaded tubular portion projecting through said opening and an enlarged head bearing against the inner wall of said protuberance, and a nut member engaging the screw threads of said tubular portion and bearing against 115 120 125 130

the exterior surface of said protuberance.
5 7. A liquid feeding device comprising a tank having a top made of a single piece of pressed sheet metal formed with a dome-like protuberance, having flat side walls, and laterally extending pipe fittings secured to said flat side walls.

10 8. A liquid feeding device comprising a distributing chamber, a suction chamber having a liquid inlet port, a valve between said chambers, a float for controlling said valve, a liquid seal chamber encircling the float, a trough on the exterior of said liquid seal chamber communicating with a trough 15 on the interior of the liquid seal chamber, a float controlled valve for closing the inlet port of the suction chamber when the liquid therein attains a predetermined abnormal level, and a housing around the last mentioned float having a discharge opening in one side adapted to deliver liquid into the trough on the exterior of the liquid seal chamber.

20 9. A liquid feeding device comprising a distributing chamber, a suction chamber, a valve between said chambers, a float for controlling said valve, a liquid seal chamber encircling the float, a shallow cup carried by the bottom of said float cooperating with the 25 lower edge of the liquid seal chamber, and an aperture in the bottom of said cup to facilitate the breaking of the seal in the liquid seal chamber.

25 10. A liquid feeding device comprising a distributing chamber, a suction chamber, a valve between said chambers, a float for controlling said valve, a liquid seal chamber encircling the float, a shallow cup carried by the bottom of said float cooperating with the 30 lower edge of the liquid seal chamber, and a spout having a corrugated edge leading from the bottom of the said cup to facilitate the breaking of the seal in the liquid seal chamber.

35 11. A liquid feeding device comprising a distributing chamber, a suction chamber, a valve between said chambers, a float in the suction chamber, valve-actuating connections extending through the valve opening, 40 said connections including a valve stem on which the valve is mounted, and a guide link pivoted at one end to the valve stem and at the other end to a fixed part of the device.

45 12. A liquid feeding device comprising a distributing chamber, a suction chamber, a valve between said chambers, a float in the suction chamber, valve-actuating connections extending through the valve opening, 50 said connections including a valve stem on which the valve is mounted and a guide link pivoted at one end to the valve stem at the distributing chamber side of the valve and at the other end to a wall of the distributing 55 chamber.

13. A liquid feeding device comprising a distributing chamber, a suction chamber, a valve between said chambers arranged at an angle to a horizontal plane, a float in the suction chamber, valve-actuating connections extending through the valve opening, 70 said connections including a valve stem on which the valve is loosely mounted, and a guide link pivoted at one end to the valve stem at the distributing chamber side of the valve and at the other end to a wall of the distributing chamber, said link having a part adapted to constitute a stop to engage the lower edge of the valve.

14. In combination, a vacuum chamber, an auxiliary chamber, a separating plate therebetween, said separating plate having a plurality of ducts leading through said plate through one of which a fluid may descend, 75 through another of which a fluid may ascend, and a single means for interrupting the passage of fluids through both of said ducts.

15. In combination, a vacuum chamber, an auxiliary chamber, a separating plate therebetween, said separating plate having a plurality of ducts leading through said plate, through one of which a fluid may descend, through another of which a fluid may ascend, 80 and means for simultaneously interrupting the passage of fluids through both of said ducts.

16. In combination, a vacuum chamber, an auxiliary chamber, a separating plate therebetween, said separating plate having a plurality of ducts leading through said plate, through one of which a fluid may descend, through another of which a fluid may ascend, and means dependent on the level of the liquid in one of said chambers for interrupting the passage of fluids through both of said ducts.

17. In combination, a vacuum chamber, an auxiliary chamber, a separating plate therebetween, said separating plate having a plurality of ducts leading through said plate, through one of which a fluid may descend, through another of which a fluid may ascend, and means dependent on the level of the liquid in one of said chambers for simultaneously interrupting the passage of fluids through both of said ducts.

18. In combination, a vacuum chamber, an auxiliary chamber, a separating plate therebetween, said separating plate being provided with a passageway through which a fluid may descend, said passageway having a conduit through which a fluid may ascend, and a single means for closing said passageway.

19. In combination, a vacuum chamber, an auxiliary chamber, a separating plate therebetween, said separating plate being provided with a passage-way through which a fluid may descend, said passage-way having 130

a conduit through which a fluid may ascend, and means extending across the bottom of said conduit for closing said passageway.

20. In combination, a vacuum chamber, an auxiliary chamber, a separating plate therebetween, said separating plate being provided with a passageway through which a fluid may descend, said passageway having a conduit through which a fluid may ascend, and means extending across the bottom of said conduit and dependent on the level of the liquid in one of said chambers for closing said passageway.

21. In combination, a vacuum chamber, an auxiliary chamber, a separating plate therebetween, said separating plate being pro-

vided with a passageway through which a fluid may descend, said passageway having a conduit through which a fluid may ascend, and means extending across the bottom of said conduit and dependent on the level of the liquid in said vacuum chamber for simultaneously closing said passageway.

22. In combination, a separating plate provided with an aperture, a collar within said aperture, a pipe within said collar, and a closure capable of controlling movement of fluids through said aperture.

Signed by me at Boston, Massachusetts, this 9th day of December, 1919.

JOSEPH C. COULOMBE.
